UNITED STATES PATENT OFFICE.

T. ROLLASON HARTELL AND JOHN LETCHWORTH, OF PHILADELPHIA, PA.

DESIGN FOR MEDALS.

Specification forming part of Design No. 7,829, dated November 3, 1874; application filed September 10, 1874.
[Term of Patent 3½ years.]

To all whom it may concern:

Be it known that we, T. ROLLASON HARTELL and JOHN LETCHWORTH, of Philadelphia, in the county of Philadelphia and State of Pennsylvania, have invented a certain new and Improved Design for Medals; and we do hereby declare the following to be a full, clear, and exact description of the same, reference being had to the accompanying drawings, which form part of this specification, in which—

Figure 1 is a view of the design of the obverse, and Fig. 2 a view of the reverse, side of the medal.

Our design for a medal consists of, first, a representation on one side of said medal of Carpenter's Hall, in the city of Philadelphia, Pennsylvania; second, a representation on the other side of said medal of the signing of the Declaration of Independence of the United States of America.

Fig. 1, in the accompanying fac-simile, is a view of Carpenter's Hall, and Fig. 2 an illustration of the signing of the Declaration of Independence of the United States of America,

which designs are applied, respectively, to the obverse and reverse sides of a medal in any suitable and appropriate manner.

What we claim as our design is—

1. A medal, bearing on one side a view of Carpenter's Hall, Philadelphia, Pennsylvania, as described and shown.

2. A medal, bearing on one side an illustration of the signing of the Declaration of Independence of the United States of America, as shown.

3. A medal, bearing on one, or the obverse, side a view of Carpenter's Hall, Philadelphia, Pennsylvania, and on the other, or reverse, side an illustration of the signing of the Declaration of Independence, substantially as shown and described.

In testimony that we claim the foregoing, we have hereunto set our hands this 8th day of September, 1874.

T. ROLLASON HARTELL.
JOHN LETCHWORTH.
